UNITED STATES PATENT OFFICE.

ALFRED HENRY HANCE SACK, OF KALKASKA, MICHIGAN.

SHIPPING-PACKAGE.

SPECIFICATION forming part of Letters Patent No. 651,726, dated June 12, 1900.

Application filed February 20, 1900. Serial No. 5,988. (No model.)

To all whom it may concern:

Be it known that I, ALFRED HENRY HANCE SACK, a citizen of the United States, residing at Kalkaska, in the county of Kalkaska and State of Michigan, have invented certain new and useful Improvements in Shipping-Packages; and I do hereby declare the following to be a full, clear, and exact description of the invention, such as will enable others skilled in the art to which it appertains to make and use the same.

My invention relates to packages for shipping perishable goods and liquids, and relates more particularly to a tank or cylinder of such construction as will best adapt it to accomplish the objects of my invention, which are, first, to provide a tank of non-corrosive material that can be manufactured at small cost and that shall be convertible for handling different classes of goods—such as liquids, which require wooden packages, and meats, &c., that are best transported in metal packages—and at the same time be simple in construction, and, second, to provide a metal cylinder having removable and reversible ends that permit the contents of the package to be readily inspected from either end and to provide for the metal cylinder a removable inner wooden lining so arranged as to form, together with the reversible ends, a shipping-tank that may be used convertibly for liquids or solid perishable goods, as above stated.

The invention is shown in the accompanying drawings, throughout the several views of which similar letters and characters of reference designate corresponding parts and devices.

In the drawings, Figure 1 is a view of the cylinder, broken away in parts, the heads or ends being removed. Fig. 2 is a sectional view of one head. Fig. 3 is a top view of the head. Fig. 4 shows the key or handle for removing the heads.

As is shown in the drawings, the device consists in a cylindrical body comprising an outer shell 1, of sheet metal, preferably coated with zinc and reinforced near its extremities by metal bands 2, secured to the shell by shrinking or otherwise. Within the metal

shell is a removable wooden lining 3, cylindrical in form, which fits the interior of the shell 1. This lining may be built up after the manner of a barrel, bound with hoops, or in any suitable manner.

Two heads or ends 4 and 5 are provided. In practice I prefer to make these ends by first pressing sheet metal into the form of a pan 4^a, that fits the interior of the metal shell 1, and then to coat the pan so formed with zinc. A circular piece of wood 4^b fits into the metal pan 4^a and is secured by zinc-coated rivets 4^c. A screw-thread 4^d is preferably pressed into the rim of the pan 4^a, and a corresponding thread is provided at each end of the cylinder 1 to receive it.

Two pairs of holes 6 and 7 are provided for each head, one pair on each side, and adapted to receive corresponding projections 6^a of the key or handle, Fig. 4, by which the heads may be unfastened or tightened. Outer stiffening or projecting strips 8, secured together and bound to the cylinder 1 by straps 9, as shown in Fig. 1, are provided when the packages are shipped with rough freight, the strips 8 serving to prevent damage to the metal cylinder from accidental blows.

By means of the devices above described I produce a shipping-tank that is not bulky and is strong and of light weight, thus effecting a saving in freight. The metal case is germ-proof and odor-proof and will not absorb impurities from the air. There is no evaporation of the contents of the package, for the head, after being screwed in place, may be hermetically sealed around the threads with wax or paraffin. The inner wood lining may be provided at its ends with suitable gaskets, if desired, and the wooden heads 4^b when screwed down make tight joints with the ends of the wood lining, thus forming a removable wooden tank within the outer air-tight casing. As above noted, liquids of various sorts may be shipped in the inner wooden lining, and when the lining is removed the metal cylinder may be used to ship butter, meats, &c.

What I claim is—

The convertible shipping-package herein described, comprising in combination a cylin-

drical metal shell threaded at both ends; reversible heads formed of pressed sheet metal and threaded to screw into the ends of the metal shell, said heads being lined on one side 5 with wood; together with an independent removable wooden cylinder adapted to fit within the metal shell and together with said heads to form a wood-lined receptacle within the

outer shell, all arranged substantially as described and for the purposes set forth. 10

In testimony whereof I affix my signature in presence of two witnesses.

ALFRED HENRY HANCE SACK.
